[57] **CLAIM**

The ornamental design for a combined multiple-unit motor fuel dispenser, as shown and described.

DESCRIPTION

FIG. 1 is a left end elevational view of a combined multiple-unit motor fuel dispenser showing my new design;

FIG. 2 is a front elevational view thereof;

FIG. 3 is a right end elevational view thereof; and

FIG. 4 is a top plan view as taken from line 4—4 of FIG. 2.

The rear view is a mirror image of FIG. 2, and the top and bottom surfaces are flat, plain and unornamented.
